UNITED STATES PATENT OFFICE.

CLIFTON W. SHERMAN, OF BUFFALO, NEW YORK, ASSIGNOR TO PRATT & LETCHWORTH COMPANY, OF BUFFALO, NEW YORK, A CORPORATION OF NEW YORK.

JOURNAL-BOX.

1,007,899.

Specification of Letters Patent. Patented Nov. 7, 1911.

Application filed June 5, 1911. Serial No. 631,345.

To all whom it may concern:

Be it known that I, CLIFTON W. SHERMAN, a citizen of the United States, residing at Buffalo, in the county of Erie and State 5 of New York, have invented new and useful Improvements in Journal-Boxes, of which the following is a specification.

This invention relates generally to a journal box for railway cars and more particularly to journal boxes of that type in which the lid is held in its closed position by spring pressure.

In some forms of journal boxes the spring mechanism designed to hold the lid yielding 15 in its closed position is not entirely satisfactory inasmuch as the pressure of the springs is not effectively exerted against the lid during the last part of its closing movement which permits the lid to swing more 20 or less into an open position and thus allows dust and dirt to reach the bearing surfaces of the journal and journal bearing and also permits the oil or waste to escape from the box or to dry out. Furthermore, 25 the spring devices heretofore in use for this purpose were so designed that dust, dirt and rain could enter the spring pocket or chamber and thus interfere with the proper operation of the spring mechanism.

30 It is the object of this invention to provide a spring holding device for the lids of journal boxes which will hold the lid firmly in its closed position and which will effectively exclude dirt, dust and rain from the 35 spring chambers and thus maintain the bearing surfaces of the journal and journal bearing in the highest state of efficiency and also prevent interference with the operation of the lid holding springs.

40 In the accompanying drawings consisting of 4 sheets: Figure 1 is a side elevation of one form of journal box embodying my improved lid closing device. Fig. 2 is a top plan view thereof. Figs. 3 and 4 are vertical longitudinal sections in the correspondingly numbered lines in Fig. 2, the lid being represented in its closed position in Fig. 3 and in its open position in Fig. 4. Fig. 5 is a fragmentary horizontal section in line 45 5-5, Fig. 4. Fig. 6 is a vertical transverse section in line 6-6, Fig. 3. Fig. 7 is a perspective view of the spring follower of the lid closing mechanism. Fig. 8 is a fragmentary vertical cross section taken in line 50 8-8, Fig. 10 and showing a form of journal

box and lid closing device embodying my invention but differing slightly from that shown in Figs. 1 to 7. Fig. 9 is a fragmentary horizontal section in line 9-9, Fig. 8. Fig. 10 is a vertical longitudinal section in line 10-10, Fig. 8. Fig. 11 is a perspective view of the follower of the lid closing mechanism shown in Figs. 8 to 10.

Similar numerals of reference indicate corresponding parts throughout the several 65 views.

In its general organization the journal box shown in Figs. 1 to 6 comprises a hollow body or box proper 1 having an opening 2 at its rear end through which the car journal projects into the body and an opening 3 at its front or outer end through which the bearing surfaces of the journal and journal bearing are accessible for inspection, repairs or supplying lubrication. 70 On its upper side the body is provided with a single hinge lug 4 projecting upwardly from the central part of the top of the box adjacent to the front opening thereof. A vertically swinging lid or cover 5 is adapted 75 to close the front opening of the body and the same is provided at its upper edge with a pair of spaced hinge lugs 6 which receive the hinge lug of the body between them. A horizontal hinge pin or pintle 7 passes 80 through coinciding openings in the hinge lugs of the body and the lid and pivotally connects these parts.

My improved lid closing mechanism designed to coöperate with the construction 90 of journal box shown in Figs. 1-6 for holding the lid in its closed position is constructed as follows: 8, 8 represent two spring chambers or pockets formed in the upper side of the body on opposite sides of the hinge lug thereof and opening upwardly toward the underside of the hinge lugs of the lid. Each of these spring pockets terminates at its upper edge in a rectangular flange which projects above the top of the body of the 95 journal box so as to form a straight transverse wall 9 on the rear side of the pocket and straight longitudinal walls 10, 11 on the inner and outer longitudinal sides thereof, as shown in Fig. 5. Within each of 100 these pockets is arranged a spring 12 preferably of helical form which is seated at one end on the bottom of this pocket. Each of the hinged lugs of the lid is provided 105 with a peripheral face 13 which is substan- 110

tially concentric with its axis throughout the greater part of this surface and provided with a receding flat face 14 adjacent to the inner side of the lid forming a corner 5 or heel 15 between the concentric and flat faces of this hinged lug so that this lug operates as a cam in a manner to be presently described.

The pressure of the springs is brought to 10 bear against the underside of the periphery of the hinged lugs of the lid by means of a follower having two presser plates, heads or covers 16 each of which extends over one of the spring pockets and bears on the underside of its front end against the upper end of the spring therein while the upper side of its front end bears against the underside of the periphery of the adjacent lid hinge lug, and a connecting bar 17 arranged transversely over the body of the box in rear of the lug thereof and connecting the rear parts of the spring covers or plates so that the follower as a whole has substantially the form of the letter U. Each of the springs 12 is 15 held against lateral displacement relatively to the follower or presser plate by means of studs 19 projecting downwardly from the underside of the respective presser plate and arranged within the upper end of the adjacent spring.

The rear parts of the heads or presser plates of the follower rest on their undersides upon the rear walls of the spring pockets so that the follower is fulcrumed 20 on the edges of these walls of the spring pockets and is capable of swinging vertically as it changes its position in following the cam-shaped peripheries of the hinged lugs of the lid. The follower is held against 25 movement in a direction lengthwise of the body of the box by means of rear stops 18 formed by transverse flanges depending from the rear edges of the presser plates and engaging with the rear or outer sides of the 30 transverse rear walls of the spring pockets, and front stops or retaining lugs 20 one of which projects downwardly from the underside of each presser plate and is adapted to engage with the inner side of the rear 35 wall of one of the spring pockets.

Upon swinging the lid upwardly into its open position the salient parts of the peripheries of the lugs thereof cause the front ends of the follower plates to be depressed 40 and the springs in the pockets to be compressed, and while thus open, the lid is held in this position by frictional contact of the concentric portions of its hinged lugs with the spring pressed bearing plates of the follower. Upon depressing the lid into its 45 closed position the front ends of the bearing plates of the follower will be held in engagement with the corners or heels 15 of the hinged lugs of the lid and hold the lid 50 firmly in its closed position, thereby pre-

venting the entrance of dirt and grit into the body of the journal box. Upon thus moving the lid into its open and closed positions the follower is prevented from moving lengthwise relatively to the body of the box 70 by means of the rear flanges and front lugs 20 thereon which are arranged on the front and rear sides respectively of the rear walls of the spring pockets. The follower is thus compelled to fulcrum on the rear walls of the pockets and is held in a position in which the springs press the same effectively against the corners or heels of the hinge lugs of the lid and hold the latter firmly in its closed position so that the same will not 80 chatter or rattle while in use and also effectively exclude all dirt, dust and rain from the interior of the journal box.

Transverse movement of the spring pressed follower is effected partly by reason 85 of its studs 19 engaging with the springs and partly by longitudinal stop flanges 21, 22 arranged on the underside of each presser plate and extending forwardly from the rear flange 18 and engaging with the 90 outer sides of the longitudinal walls of the adjacent spring pocket.

The front ends of the bearing plates of the follower extend underneath the hinge lugs of the lid while the longitudinal and 95 rear edges of each of these plates extend over the longitudinal and rear transverse walls of the pockets. Transverse movement of the follower is prevented by the stop flanges 21, 22 engaging with the outer sides 100 of the longitudinal walls of the spring pockets and also by engagement of the inner stops 20 with the inner sides of the outer longitudinal walls of the spring pockets, as shown in Fig. 5.

By this arrangement and construction of the follower the spring pockets are completely covered, thereby excluding dust, dirt and rain from these pockets and avoiding interference with the springs into the same, whereby the life of the latter is prolonged 110 and the efficiency thereof is maintained.

The construction of journal box shown in Figs. 8, 9 and 10 is a reversal of the constructions shown in Figs. 1 to 6, viz: the body 23 of the journal box is provided with two hinge lugs 24, 24, and the lid 15 is provided centrally at its upper end with a single hinge lug 26 which is arranged between the hinge lugs of the body and pivotally connected therewith by means of a horizontal hinge pin or pintle 27. In applying my improvements to this form of journal box the upper side of the body is provided between the hinge lugs thereof with a single spring pocket 28 which opens upwardly toward the hinge lug of the lid. Within this pocket and at opposite ends thereof is arranged a pair of helical springs 29 which rest at their lower ends on the bottom of the pocket. Be- 125 130

- tween the upper ends of the springs and the hinge lugs of the lid is arranged a follower or presser plate 30 which is adapted to be depressed by the high concentric face 31 on 5 the hinge lug of the lid and permitted to rise under the action of the springs 29 by the receding face 32 of the lid hinge lug. The follower extends rearwardly and laterally over the rear and side walls of the spring 10 pocket so as to exclude dust, dirt and rain therefrom and longitudinal movement of this follower is prevented by means of a downwardly projecting transverse stop flange 33 formed thereon and engaging with 15 the outer side of the rear wall of the spring pocket, and a pair of stops or retaining lugs 34 projecting downwardly from the underside of the follower and adapted to engage with the inner side of the rear wall of the 20 pocket. By this means the follower is compelled to turn on said rear wall as a fulcrum and the lid is held reliably in position for causing the follower to bear effectively against the corner of the lid hinge lug and 25 hold the lid reliably in its closed position.
- In both forms of journal boxes and lid holding devices shown in Figs. 1-11, the pressure plates or followers are held against longitudinal movement and are fulcrumed on 30 the rear walls of the spring pockets so that the springs exert their full pressure at all times on the hinge lugs of the lid, particularly when the same is closed, thereby preventing lost motion between the lid and the 35 spring closing device and avoiding the objectionable results which otherwise would occur.
- I claim as my invention:
1. A journal box comprising a body provided with a hinge lug and a pocket adjacent to said lug, a lid having a hinge lug which is pivotally connected with the hinge lug of the body and which has a cam-shaped periphery, a presser plate engaging with the 40 periphery of the hinge of the lid and pivotally supported on one edge of the spring pocket, and a spring arranged within the spring pocket and bearing against the free end of said plate.
  2. A journal box comprising a body provided with a hinge lug and a pocket adjacent to said lug, a lid having a hinge lug which is pivotally connected with the hinge lug of the body and which has a cam-shaped periphery, a presser plate engaging with the 45 periphery of the hinge of the lid and the rear edge of said pocket and provided with a
  - flange engaging the outer side of the rear wall of said pocket and a spring arranged in said pocket and engaging with said plate. 60
  3. A journal box comprising a body provided with a hinge lug and a pocket adjacent to said lug, a lid having a hinge lug which is pivotally connected with the hinge lug of the body and which has a cam-shaped periphery, a presser plate engaging with the periphery of the hinge of the lid and the rear edge of said pocket and provided with a flange engaging the outer side of the rear wall of said pocket and with flanges engaging the outer sides of the side walls of said pocket and a spring arranged in said pocket and engaging with said plate. 65
  4. A journal box comprising a body provided with a hinge lug and a pocket adjacent to said lug, a lid having a hinge lug which is pivotally connected with the hinge lug of the body and which has a cam-shaped periphery, a presser plate engaging with the periphery of the hinge of the lid and the rear edge of said pocket and provided with a flange engaging the outer side of the rear wall of said pocket, and with a depending lug engaging the inner side of the rear wall of said pocket, and a spring arranged in said 70 pocket and engaging with said plate. 75
  5. A journal box comprising a body provided on its upper side with a hinge lug and on opposite sides of said lug with spring pockets each of which opens upwardly and is provided with a transverse rear wall and longitudinal inner and outer walls, a lid provided at its upper end with a pair of hinge lugs arranged on opposite sides of the hinge lug of the body and each lug of the 80 lid having its periphery constructed to form a cam, a follower having two presser plates bearing at their front ends against the underside of the peripheries of said lid hinge lugs while their rear ends rest pivotally on the rear walls of said pockets, depending projections arranged on the presser plates in front and in rear of said rear walls of the 85 pockets and a cross bar connecting said plates, and springs arranged in said pockets and bearing against the underside of said plates at the front ends thereof. 90
  - Witness my hand this 31st day of May 1911.
